DESIGN FOR A PADLOCK

William H. Booth, New Britain, Conn., assignor to The American Hardware Corporation, New Britain, Conn., a corporation of Connecticut

Application September 28, 1935, Serial No. 58,753

Term of patent 7 years

To all whom it may concern:

Be it known that I, William H. Booth, a citizen of the United States and a resident of New Britain, in the county of Hartford and State of Connecticut, have invented a new, original, and ornamental Design for a Padlock, of which the following is a specification, reference being had to the accompanying drawing, forming part thereof, in which—

The characteristic feature of my design resides in the facial ornamentation of the lock body of the configuration shown, such ornamentation being in the form of raised ribs arranged in spaced pairs with the intermediate pair broken and intersected by an oval frame.

I claim:

The ornamental design for a padlock, as shown and described.

WILLIAM H. BOOTH.
